UNITED STATES PATENT OFFICE.

JOHN N. WATT, OF STOCKTON, CALIFORNIA.

PROCESS OF DISTILLATION.

No. 851,718.

Specification of Letters Patent.

Patented April 30, 1907.

Application filed March 18, 1905. Serial No. 250,858.

To all whom it may concern:

Be it known that I, JOHN NELSON WATT, a citizen of the United States, residing at Stockton, in the county of San Joaquin and State of California, have invented certain new and useful Improvements in Process of Distillation, of which the following is a specification.

This invention relates to an improved process of distilling brandy or other spirits from wine and other fermented liquors, the object of the invention being to provide a process by which such distillation may be effected more rapidly than heretofore and at the same time so as to separate from the distillate the deleterious ingredients present in the original fermented liquor.

In the accompanying drawing, the figure is a side elevation, partly in section, of an apparatus suitable for carrying out the above process.

Referring to the drawing, 1 represents a boiler of any convenient form in which any fermented liquor is introduced through openings 2, the interior of said boiler being heated by a steam coil 3, controlled by a valve 23. The vapors generated by the heating of such liquor are passed through a pipe 4 to a coil of pipe 5 in a condenser 6, filled with water by a pipe 7, controlled by a valve 27; and with an outlet 8, controlled by a valve 28. Steam is introduced into this condenser by a steam pipe 9, controlled by a valve 29, and a thermometer 10 indicates the temperature therein. The liquids and vapors from said coil 5 are discharged by a pipe 11, controlled by a valve 31, into a closed vessel 12, which is provided with a glass window 13 opposite to the bottom of said pipe 11, through which window it can be seen whether the material discharged therefrom is in the form of liquid or vapor. From the top of said vessel 12 a pipe 14 leads to a suction pump 15, operated by a wheel 30, driven by a belt 32, and thence by a pipe 33, controlled by a valve 34, to a chamber 16, discharging beneath the lowest of a series of baffle plates 17 therein; from which chamber 16 the uncondensed vapor discharges by a pipe 18. Air can be introduced into the chamber 12 by means of a pipe 19 controlled by a valve 20.

The process of distillation by means of this apparatus is as follows:—The fermented liquor having been introduced into the boiler and heated to a temperature just sufficient to generate the lightest vapors, 100 to 120

degrees Fahrenheit, and the exhaust pump having been set in operation to a degree of vacuum varying from the highest practicable vacuum to approximately one-third of the atmospheric pressure, the vapors so generated are allowed to escape by the pipe 4 into coil 5, and are partly condensed therein. It is found in practice that more volatile portions, such as the ether and fixed gases, load themselves with or entrain the fusel oil, and escape into the vessel 12 and then from said vessel through the pipe 14. It is believed that this result arises from said ether and fixed gases having a greater affinity for the fusel oil than the liquid spirits.

On the commencement of the operation, the most volatile constituents of the liquor, such as the ether and gases, carrying with them most, if not all, of the fusel oil, escape in large quantities. It is very important that none of this should be condensed, but that all of it should escape and be separated from the brandy or other spirits. Accordingly, at the commencement of the operation, the water around the coil is maintained at a comparatively high temperature, 95 to 105 degrees Fahrenheit, which is a temperature sufficiently high to insure, that the ether and gases, carrying with them a part, if not all, of the fusel oil, will pass through the coils without any portion of them becoming condensed in the coils. After the ether and gases, carrying with them most, if not all, of the fusel oil contained in the liquid in the boiler, have been disposed of in this manner, the temperature of the water surrounding the coils is reduced to a temperature sufficient to condense the alcohol vapors coming from the boiler. It is found that by the above means the resulting liquid is almost, if not absolutely, pure of fusel oil or ether, the principal deleterious ingredients of spirituous liquors. The resulting liquid is left in the chamber 12, while the ether and gases escape therefrom, being drawn up by the exhaust pump. In order to insure that none of these noxious gases are condensed in the chamber 12 the valve 31 is provided, so that by closing said valve to a greater or less extent, the degree of vacuum in the chamber 12 may be greater than that in the boiler which will prevent any condensation of any of the ether or other noxious gases in the chamber 12.

Upon passing from the exhaust pump, the vapors of ether and gases carrying the fusel oil pass into chamber 16, and can only escape

by passing around the baffle plates 17. The ether and gases, being more volatile than the fusel oil, pass off, and the fusel oil is condensed by said baffle plates, and drops to the bottom of the chamber 16, whence it can be drawn off and sold as a commercial product.

By means of the above process the distillation is effected much more rapidly than heretofore, because the vacuum created by the suction pump, which draws the deleterious fumes away from the distillate, also causes the vaporization of the fermented liquor to take place more rapidly, and at a lower temperature; this latter condition is advantageous, because it prevents carbonization of the saccharine matter, and also avoids the bursting of the minute capsules of ether and gases carrying the fusel oil.

It will be observed that with the above process both of the operations of distillation and purification are performed in a single operation, and with scarcely any extra expense in the apparatus, or in the power required, and that a brandy or whisky can be produced which at the time of production is equal in every respect to one ten years old or more, being absolutely free from ether or fusel oil.

In the case of distillation of whisky from corn or other mash, the mash is left in a sweet condition, furnishing excellent food

for cattle; whereas, in the ordinary process it remains sour.

I claim:

1. The process of distilling fermented liquors which consists in vaporizing the same under reduced pressure, and subjecting the vapors while under the reduced pressure to fractional condensation at a temperature between the condensing points of alcohol and the head products at such reduced pressure, whereby the alcohol is condensed and collected and the head products are separated therefrom, substantially as described. 35

2. The process of distilling fermented liquors which consists in vaporizing the same under reduced pressure, subjecting the vapors while under reduced pressure to fractional condensation at a temperature between the condensing points of alcohol and the head products at such reduced pressure, and then reducing the temperature of the vapors, whereby the alcohol is condensed and collected and the head products are separated therefrom, substantially as described. 45

In witness whereof I have hereunto set my hand in the presence of two subscribing witnesses.

J. N. WATT.
